ELECTRICALLY-LIFTED COMPUTER DESK AND OFFICE DESK THEREOF

This application claims priority to Chinese Patent Application Ser. No. CN201621074710X filed 23 Sep. 2016.

FIELD OF THE INVENTION

The invention relates to an electrically-lifted computer desk and office desk thereof which can be used separately or in combination and can be lifted stably with low noise and great bearing power.

BACKGROUND OF THE INVENTION

With the more and more generalization of digital homes, the household life of people are undergoing enormous changes, wherein the incorporation of digital automation design in modern digital homes is becoming the most outstanding advantage. In a household environment, the desk has been incorporated into human lives with multiple functions. On the current stage, the desk is generally used only as a dining table, a computer desk, a study desk and the like. Therefore, the functions of the desk are single at present, and can not satisfy the multi-purpose requirements.

In order to solve the above-mentioned problem, the Chinese patent CN 102599728A discloses a lifting desktop device, comprising a lifting desktop, a screw rod driving mechanism, a first bearer, two push rods and two first support rods, wherein the screw rod driving mechanism comprises synchronization wheels, a synchronization belt, a motor device, two nut sliding blocks and two screw rods; the two nut sliding blocks are respectively sleeved on the two screw rods; the two synchronization wheels are respectively disposed at the same ends of the two screw rods; the synchronization belt is connected with the two synchronization wheels; one of the two screw rods is connected with the motor device; one end of the push rod is pivotally connected with the lifting desktop, and the other end is pivotally connected with the nut sliding block; one end of the first support rod is pivotally connected with the lifting desktop, and the other end is pivotally connected with the first bearer; and the lifting desktop can be lifted upwards or folded downwards under the drive of the motor device. The lifting desktop device of the invention is suitable to be used together with various computer desks, school desks, tea tables and the like for placing a keyboard and a mouse; the lifting desktop is free to be lifted and folded, is compact and flexible, and has strong versatility and practicability.

However, the lifting desktop device has the following problems in use: first, the lifting desktop device can not be used separately, but can only be used together with a support platform; second, the structural design is unreasonable: the adoptions of two screw rods and nuts combination and a plurality of pivot joint points cause extreme instability when in operation and multiple fault points; third, the lifting desktop device can not bear a load: when a certain pressure is applied on the lifting desktop, the whole lifting desktop device will swing front and back, left and right.

BRIEF DESCRIPTION OF THE INVENTION

In order to address the deficiencies of the prior art, the invention provides the society with an electrically-lifted computer desk and office desk thereof which can be lifted stably with low noise and great bearing power.

The technical solution of the invention is: provided is an electrically-lifted computer desk, comprising a bottom plate, a driving mechanism, an intermediate support member, a first side-support member, a second side-support member and a face plate, wherein the driving mechanism is fixedly disposed on the bottom plate; the face plate is fixedly disposed on the first side-support member and the second side-support member; and the driving mechanism drives the face plate to rise or fold via the intermediate support member, the first side-support member and the second side-support member, wherein

The driving mechanism comprises a first fixing piece, a second fixing piece, a first guide rod and a second guide rod; the first fixing piece and the second fixing piece are parallel to each other, and are separated by a preset distance; the first guide rod and the second guide rod are parallel to each other, are separated by a preset distance, and form a frame together with the first fixing piece and the second fixing piece; a screw rod is disposed in parallel with the first guide rod at 15 an intermediate position between the first guide rod and the second guide rod of the frame; the two ends of the screw rod are respectively connected with the first fixing piece and the second fixing piece; a driving source is disposed at one end of the screw rod; and the driving mechanism is fixed on the 20 bottom plate via the first fixing piece and the second fixing piece.

As an improvement to the invention, the intermediate support member comprises a nut sliding rod seat, a first side-support piece, a second side-support piece and a transverse link, wherein the nut sliding rod seat is threaded on the first guide rod, the second guide rod and the screw rod of the driving mechanism, and does a reciprocating motion along the first guide rod and the second guide rod with the rotation of the screw rod; the lower end of the first side-support piece 30 is pivotally connected with one end of the nut sliding rod seat; the lower end of the second side-support piece is pivotally connected with the other end of the nut sliding rod seat; and the upper ends of the first side-support piece and the second side-support piece are fixedly connected with the 35 transverse link.

As an improvement to the invention, the first side-support member comprises a third side-support piece, a fourth side-support piece, and a first desktop connecting piece fixedly connected with the face plate, wherein the lower end 40 of the third side-support piece is pivotally connected with the bottom plate; the upper end of the third side-support piece is slidably connected with the first desktop connecting piece; the upper end of the fourth side-support piece is pivotally connected with the first desktop connecting piece; the lower end of the fourth side-support piece is pivotally connected with the middle part of the third side-support piece and one end of the transverse link.

As an improvement to the invention, the second side-support member comprises a fifth side-support piece, a sixth side-support piece, and a second desktop connecting piece fixedly connected with the face plate, wherein the lower end 55 of the fifth side-support piece is pivotally connected with the bottom plate; the upper end of the fifth side-support piece is slidably connected with the second desktop connecting piece; the upper end of the sixth side-support piece is pivotally connected with the second desktop connecting piece; the lower end of the sixth side-support piece is pivotally connected with the middle part of the fifth side-support piece and the other end of the transverse link.

As an improvement to the invention, the bottom plate is hollowed to form a first flanged edge and a second flanged edge; the lower end of the third side-support piece is

pivotedly connected with the first flanged edge; and the lower end of the fifth side-support piece is pivotally connected with the second flanged edge.

As an improvement to the invention, the first desktop connecting piece comprises a third flanged edge; the third flanged edge is provided with a first guide groove thereon; a first guide wheel is disposed at the upper end of the third side-support piece; and the third side-support piece is slidably connected with the first guide groove via the first guide wheel.

As an improvement to the invention, the second desktop connecting piece comprises a fourth flanged edge; the fourth flanged edge is provided with a second guide groove thereon; a second guide wheel is disposed at the upper end of the fifth side-support piece; and the fifth side-support piece is slidably connected with the second guide groove via the second guide wheel.

As an improvement to the invention, the electrically-lifted computer desk further comprises a keyboard plate; the two sides of the keyboard plate are respectively fixedly connected with the first desktop connecting piece and the second desktop connecting piece, or slidably connected with the first desktop connecting piece and the second desktop connecting piece via a drawer slide assembly.

The invention further provides an office desk provided with the electrically-lifted computer desk.

The invention adopts a frame-shaped driving mechanism and a frame-shaped intermediate support member; and the nut sliding rod seat of the intermediate support member is threaded on the first guide rod, the second guide rod and the screw rod of the driving mechanism, and does a reciprocating motion along the first guide rod and the second guide rod with the rotation of the screw rod. The invention not only has the advantages of stable lifting and low noise, but also has the advantage of great bearing power.

BRIEF DESCRIPTION OF DRAWINGS

FIG. 1 is a three-dimensional structure schematic diagram of one embodiment of the invention;

FIG. 2 is a three-dimensional structure schematic diagram of the embodiment in FIG. 1 from another visual angle;

FIG. 3 is a three-dimensional structure schematic diagram of the embodiment in FIG. 1 from a third visual angle;

FIG. 4 is a three-dimensional structure schematic diagram of the embodiment in FIG. 1 in a folding state;

FIG. 5 is a three-dimensional structure schematic diagram of another embodiment of the invention;

FIG. 6 is a three-dimensional structure schematic diagram of the embodiment in FIG. 5 in a folding state.

DETAILED DESCRIPTION OF THE INVENTION

Please refer to FIG. 1-4 which disclose an electrically-lifted computer desk 100, comprising a bottom plate 110, a driving mechanism 120, an intermediate support member 130, a first side-support member 140, a second side-support member 150 and a face plate 160, wherein the driving mechanism 120 is fixedly disposed on the bottom plate 110; the face plate 160 is fixedly disposed on the first side-support member 140 and the second side-support member 150; and the driving mechanism 120 drives the face plate 160 to rise or fold via the intermediate support member 130, the first side-support member 140 and the second side-support member 150, wherein

The driving mechanism 120 comprises a first fixing piece 121, a second fixing piece 122, a first guide rod 123 and a second guide rod 124; the first fixing piece 121 and the second fixing piece 122 are parallel to each other, and are separated by a preset distance; the first guide rod 123 and the second guide rod 124 are parallel to each other, are separated by a preset distance, and form a frame together with the first fixing piece 121 and the second fixing piece 122; a screw rod 125 is disposed in parallel with the first guide rod 123 at an intermediate position between the first guide rod 123 and the second guide rod 124 of the frame; the two ends of the screw rod are respectively connected with the first fixing piece 121 and the second fixing piece 122; a driving source 126 is disposed at one end of the screw rod 125; and the driving mechanism 120 is fixed on the bottom plate 110 via the first fixing piece 121 and the second fixing piece 122; the intermediate support member 130 comprises a nut sliding rod seat 131, a first side-support piece 132, a second side-support piece 133 and a transverse link 134, wherein the nut sliding rod seat 131 is threaded on the first guide rod 123, the second guide rod 124 and the screw rod 125 of the driving mechanism 120, and does a reciprocating motion along the first guide rod 123 and the second guide rod 124 with the rotation of the screw rod 125; the lower end of the first side-support piece 132 is pivotally connected with one end of the nut sliding rod seat 131; the lower end of the second side-support piece 133 is pivotally connected with the other end of the nut sliding rod seat 131; and the upper ends of the first side-support piece 132 and the second side-support piece 133 are fixedly connected with the transverse link 134. What should be understood is that when the screw rod 125 is connected with the nut sliding rod seat 131, the screw threads for connecting the nut sliding rod seat 131 with the screw rod 125 can be formed by directly threading the nut sliding rod seat 131, and can also be formed by embedding another nut in the nut sliding rod seat 131; similarly, when the nut sliding rod seat 131 is connected with the first guide rod 123 and the second guide rod 124, a hole can be directly punched on the nut sliding rod seat 131, or a sliding bush can be embedded after punching a hole on the nut sliding rod seat 131. The driving source 126 in the invention can be driven by a motor 1261; when driven by the motor 1261, two different modes are provided: one is that the motor 1261 is directly connected with one end of the screw rod 125 via a speed reducer 1265; and the other one is as shown in the figure: a first synchronization wheel 1262 is disposed on the output shaft of the speed reducer 1265 of the motor 1261, a second synchronization wheel 1263 is disposed at one end of the screw rod 125, and the first synchronization wheel 1262 is connected with the second synchronization wheel 1263 via a synchronization belt 1264. Obviously, if a more environmentally-friendly structure is required to be made, the driving source 126 can be directly driven by manpower, in which case a rocker (unshown in the figure) for applying force is required to be disposed at one end of the screw rod 125. The invention adopts a frame-shaped driving mechanism and a frame-shaped intermediate support member, and transfers the motive power via the frame-shaped intermediate support member. Therefore, the invention has the advantages of stable lifting, low noise and great bearing power.

Preferably, the first side-support member 140 comprises a third side-support piece 141, a fourth side-support piece 142, and a first desktop connecting piece 143 fixedly connected with the face plate 160, wherein the lower end 1411 of the third side-support piece 141 is pivotally connected with the bottom plate 110; the upper end 1412 of the third side-

support piece 141 is slidably connected with the first desktop connecting piece 143; the upper end 1421 of the fourth side-support piece 142 is pivotally connected with the first desktop connecting piece 143; the lower end 1422 of the fourth side-support piece 142 is pivotally connected with the middle part of the third side-support piece 141 and one end of the transverse link 134; the second side-support member 150 comprises a fifth side-support piece 151, a sixth side-support piece 152, and a second desktop connecting piece 153 fixedly connected with the face plate 160, wherein the lower end 1511 of the fifth side-support piece 151 is pivotally connected with the bottom plate 110; the upper end 1512 of the fifth side-support piece 151 is slidably connected with the second desktop connecting piece 153; the upper end 1521 of the sixth side-support piece 152 is pivotally connected with the second desktop connecting piece 153; the lower end 1522 of the sixth side-support piece 152 is pivotally connected with the middle part of the fifth side-support piece 151 and the other end of the transverse link 134.

Preferably, the bottom plate 110 is hollowed to form a first flanged edge 111 and a second flanged edge 112; the lower end of the third side-support piece 141 is pivotally connected with the first flanged edge 111; and the lower end of the fifth side-support piece 151 is pivotally connected with the second flanged edge 112.

Preferably, the first desktop connecting piece 143 comprises a third flanged edge 1431; the third flanged edge 1431 is provided with a first guide groove 1432 thereon; a first guide wheel 1413 is disposed at the upper end of the third side-support piece 141; the third side-support piece 141 is slidably connected with the first guide groove 1432 via the first guide wheel 1413; the second desktop connecting piece 153 comprises a fourth flanged edge 1531; the fourth flanged edge 1531 is provided with a second guide groove 1532 thereon; a second guide wheel 1513 is disposed at the upper end of the fifth side-support piece 151; and the fifth side-support piece 151 is slidably connected with the second guide groove 1532 via the second guide wheel 1513.

What should be explained is that when two components are pivotally connected in the invention, a bearing can be assembled at the pivot connecting position, which facilitates the rotation of the invention and reduces noise.

Preferably, the invention further comprises a keyboard plate 170; the two sides of the keyboard plate 170 are respectively fixedly connected with the first desktop connecting piece 143 and the second desktop connecting piece 153, or slidably connected with the first desktop connecting piece 143 and the second desktop connecting piece 153 via a drawer slide assembly.

Please refer to FIG. 3-4. The invention further provides an office desk; the office desk 200 is provided with the electrically-lifted computer desk 100.

The bottom plate 160 can be directly replaced with an office desk face plate to form an integrative office desk 200 provided with the electrically-lifted computer desk 100; alternatively, the bottom plate 160 can also be maintained, such that the electrically-lifted computer desk 100 can be used separately or in combination with the office desk 200, thus forming a completely novel furniture combination.

What is claimed is:

1. A desk comprising:
a bottom plate;
a first side-support member coupled to the bottom plate;
a second side-support member coupled to the bottom plate;

a face plate coupled to the first side-support member and the second side-support member;
a transverse link coupled to the first side-support member and the second side-support member;
5 a driving mechanism, the driving mechanism comprising:
a first guide rod;
a second guide rod parallel to the first guide rod;
a screw rod parallel to the first guide rod; and
a driving source configured to rotate the screw rod, and
a nut sliding rod seat coupled to the transverse link with
10 at least one side-support piece, the nut sliding rod seat
configured to move along the screw rod,
wherein the driving mechanism is configured to rotate the
screw rod moving the nut sliding rod seat to raise and
lower the face plate.

2. The desk of claim 1, further comprising:
a first fixing piece; and

a second fixing piece parallel to the first fixing piece,
wherein the first fixing piece, the second fixing piece, the
15 first guide rod, and the second guide rod form a frame.

3. The desk of claim 2, wherein a first end of the screw rod
is connected to the first fixing piece and a second end of the
screw rod is connected to the second fixing piece, and
wherein the driving source is disposed at the first end of the
20 screw rod.

4. The desk of claim 3, wherein the bottom plate is fixed
to the first fixing piece and the second fixing piece.

5. The desk of claim 1, further comprising an intermediate
support member, the intermediate support member config-
30 ured to couple the driving mechanism to the first side-
support member and the second side-support member.

6. The desk of claim 5, the intermediate support member
further comprising the nut sliding rod seat configured to
slide along the first guide rod and the second guide rod.

7. The desk of claim 5, the intermediate support member
further comprising the nut sliding rod seat, the at least one
35 side-support piece, and the transverse link,
wherein the at least one side-support piece includes a first
side-support piece coupled to the nut sliding rod seat
and a second side-support piece coupled to the nut
sliding rod seat.

8. The desk of claim 7, wherein the first side-support piece
includes a lower end pivotally connected with a first end of
40 the nut sliding rod seat, the second side-support piece
includes a lower end pivotally connected with a second end
of the nut sliding rod seat, and an upper end of the first
side-support piece and an upper end of the second side-
support piece are fixedly connected with the transverse link.

9. The desk of claim 1, wherein the nut sliding rod seat is
50 coupled to the first guide rod, the second guide rod, and the
screw rod, and wherein the nut sliding rod seat is in threaded
engagement with the screw rod for reciprocating motion
along the first guide rod and the second guide rod upon
rotation of the screw rod.

10. The desk of claim 1, wherein the first side-support
member and the second side-support member are each
55 slidably coupled to the face plate.

11. The desk of claim 1, wherein the first side-support
member and second side-support member each comprise a
60 side-support piece having an upper end and a lower end,
wherein the upper end of each side-support piece is pivotally
connected to a respective desktop connecting piece fixedly
connected with the face plate and wherein the lower end of
each side-support piece is pivotally connected to a trans-
verse link.

12. The desk of claim 1, wherein the first side-support
member and second side-support member each comprise a

side-support piece having an upper end and a lower end, wherein the upper end of each side-support piece is slidably coupled to a respective desktop connecting piece fixedly connected with the face plate and wherein the lower end of each side-support piece is pivotally connected to the bottom plate.

13. The desk of claim 12, further comprising an intermediate support member, the intermediate support member configured to couple the screw rod to the first side-support member and the second side-support member.

14. The desk of claim 13, wherein the intermediate support member comprises the transverse link extending between the first side-support member and the second side-support member.

15. The desk of claim 14, wherein the first side-support member and second side-support member each comprise a second side-support piece having an upper end and a lower end, wherein the upper end of each second side-support

piece is pivotally connected to the respective desktop connecting piece fixedly connected with the face plate and wherein the lower end of each second side-support piece is pivotally connected to the transverse link.

5 16. The desk of claim 14, wherein the intermediate support member further comprises the nut sliding rod seat that slides along the first guide rod and the second guide rod, and is in threaded engagement with the screw rod.

10 17. The desk of claim 1, wherein the driving source comprises a motor.

15 18. The desk of claim 1, further comprising a keyboard plate, the keyboard plate coupled with a first desktop connecting piece and a second desktop connecting piece, wherein the first desktop connecting piece and the second desktop connecting piece are fixedly connected to the face plate.
